[57] CLAIM

The ornamental design for a breakfront or the like, substantially as shown and described.

DESCRIPTION

FIG. 1 is a front elevational view of a breakfront or the like showing my new design;

FIG. 2 is a top plan view thereof; and
FIG. 3 is a right side elevational view, the left side being a mirror image thereof.

The rear of the breakfront or the like is flat and unornamented.

FIG. 3.
